CLAIM

The ornamental design for a wafer paddle, as shown and described.

DESCRIPTION

FIG. 1 depicts a front perspective view of a first embodiment of a wafer paddle.

FIG. 2 depicts a close-up view labeled in FIG. 1.

FIG. 3 depicts a close-up view labeled in FIG. 1.

FIG. 4 depicts a left elevation view of the wafer paddle of FIG. 1.

FIG. 5 depicts a close-up view labeled in FIG. 4.

FIG. 6 depicts a right elevation view of the wafer paddle of FIG. 1.

FIG. 7 depicts a close-up view labeled in FIG. 6.

FIG. 8 depicts a top plan view of the wafer paddle of FIG. 1.

FIG. 9 depicts a bottom plan view of the wafer paddle of FIG. 1.

FIG. 10 depicts a rear elevation view of the wafer paddle of FIG. 1; and,

FIG. 11 depicts a front elevation view of the wafer paddle of FIG. 1.

The broken lines in the drawings illustrate environmental structure on the article and form no part of the claimed design.
